James Norton & John Martino, of Philadelphia, Pa.
Assignors to
D. Stewart and R. Peterson, of same place.
Letters Patent No. 1314. Dated Sept. 25, 1860.

The schedule referred to in these Letters Patent, and making part of the same.

To all whom it may concern:

Be it known that we, James Norton, and John Martino, both of the City and County of Philadelphia, State of Pennsylvania, have invented or produced a new and original design for a stove turned the "Norton," and we do hereby declare the accompanying drawings and following explanation of the same to form a full, clear, and exact description of the said design.

The accompanying drawings, Nos. 1 & 2 represent the stove in perspective, with different styles of caps.

Dec. 13/14

The body A. of the Stove which is of the oval form illustrated has a series of rounded flutes and is furnished with a scrolloped ring B.

The base C. and bottom plate D. are ornamented with denticulated beads and other ornaments illustrated in the two perspective views -

We claim the combination of ornamental figures and forms represented in and by the accompanying drawing, forming together an ornamental design for the body, base, and bottom plate of a stove.

In testimony whereof we have signed our names to this specification in the presence of two subscribing witnesses -

Witnesses. {
Henry Howson, }
G. A. Richards. }
